MAGNETIC TAPE VIDEO CASSETTE MACHINE

Darrell S. Staley, San Jose, Calif., assignor to Ampex
Corporation, Redwood City, Calif.

Filed Mar. 19, 1971, Ser. No. 126,389

Term of patent 14 years

Int. Cl. D14—02

U.S. Cl. D26—5

The sole figure is a front and left side perspective view of a magnetic tape video cassette machine showing my new design, the right side being a mirror image of the left side, and the back, top and bottom being conventionally plain.

I claim:

The ornamental design for a magnetic tape video cassette machine, substantially as shown and described.
